UNITED STATES PATENT OFFICE

BENJAMIN S. NASH, OF SHORT HILLS, NEW JERSEY, ASSIGNOR TO THE STEARNS & FOSTER COMPANY, OF LOCKLAND, OHIO, A CORPORATION OF OHIO

DESIGN FOR A TEXTILE FABRIC

Application filed September 25, 1929. Serial No. 32,866. Term of patent 7 years.

To all whom it may concern:

Be it known that I, BENJAMIN S. NASH, a citizen of the United States, residing at Short Hills, in the county of Essex and State of New Jersey, have invented a new, original, and ornamental Design for Textile Fabric, of which the following is a specification, reference being had to the accompanying drawing, forming part thereof.

In the drawing:—

The figure is a plan view of a piece of tex-

tile fabric showing my design, a repeat unit of which is contained within the area outlined by dot and dash lines terminating in arrow heads, such unit being repeated in the relation indicated by the extension of the design on each side of the dot and dash lines.

I claim:

The ornamental design for textile fabric substantially as shown and described.

BENJAMIN S. NASH.
